BARREL-ENCLOSING CABINET FOR BREW- DISPENSING ESTABLISHMENTS

Arthur H. Patch, Glen Ridge, N. J.

Application May 4, 1949, Serial No. 2,432

Term of patent 14 years

(Cl. D2—3)

To all whom it may concern:

Be it known that I, Arthur H. Patch, a citizen of the United States of America, residing in Glen Ridge, in the county of Essex and State of New Jersey, have invented a new, original, and ornamental Design for a Barrel-Enclosing Cabinet for Brew-Dispensing Establishments, of which the following is a specification, reference being had to the accompanying drawing, forming a part thereof, wherein:

Fig. 1 is a front perspective view of a barrel-enclosing cabinet for brew-dispensing establishments, showing my new design; and

Fig. 2 is a rear perspective view thereof.

I claim:

The ornamental design for a barrel-enclosing cabinet for brew-dispensing establishments, substantially as shown.

ARTHUR H. PATCH.
